UNITED STATES PATENT OFFICE.

EDWARD B. WESTON, OF DAYTON, OHIO, ASSIGNOR TO WESTON PAPER AND MFG. CO., OF DAYTON, OHIO, A CORPORATION OF OHIO.

DISPLAY STAND.

Original application filed November 4, 1924, Serial No. 747,748. Divided and this application filed July 30, 1925. Serial No. 46,963.

To all whom it may concern:

Be it known that I, EDWARD B. WESTON, a citizen of the United States, and resident of Dayton, in the county of Montgomery and 5 State of Ohio, have invented certain new and useful Improvements in Display Stands, of which the following is a specification.

This invention is an improvement in display stands, and more particularly in card holder attachments for stands of the knock 10 down or foldable type.

Stands of the character in question are usually supplied to the retailer with selected quantities of packages of merchandise for 15 displaying such merchandise. Usually the stand is shipped with the merchandise and proportioned to hold a definite quantity thereof.

Since the stand is used partly at least for 20 the benefit of the manufacturer, it is desirable that the stands should be furnished, if not free of charge, as cheaply as possible. It is also desirable that the stands be provided with means in the way of display matter, calling attention to the merits of the 25 goods displayed thereon.

To be attractive, the display should be of a nature such that it may be changed at intervals, to display new matter, and the displayed matter should be in as prominent a position as possible, preferably supported 30 by the stand above the goods, but not in such a manner as to add permanent height to the stand.

One of the objects of the present invention 35 is the provision in a stand of this character, of means for displaying matter relating to the goods supported by the stand, normally within the overall limits of the stand, capable of extension beyond such limit, and wherein the display matter is capable of being changed at intervals.

With this and other objects in view the invention consists in the construction and 45 novel combination of parts fully described hereinafter, illustrated in the accompanying drawings, and pointed out in the claims appended hereto, it being understood that various changes in the form, proportion, size 50 and minor details of construction within the scope of the claims, may be resorted to without departing from the spirit of the invention.

In the drawings:

Fig. 1 is a perspective view of the stand 55 with the display supporting mechanism extended.

Fig. 2 is a front view of the stand back with the display mechanism in normal retracted position.

Fig. 3 is a section on the line 3—3 of Fig. 2.

The present invention is a division of application Ser. No. 747,748, filed Nov. 4, 1924, and the display mechanism is shown in connection with the stand forming the subject matter of the said application.

The stand comprises a seat 1, pairs of supporting legs 2 and 3, and an inverted substantially U-shaped back, comprising a 70 body 4 and arms 5. The body and arms are of angle material as shown, and the arms are connected by cross bars 6 and 7, the latter being near the seat, while the former is intermediate the length of the arms.

The display mechanism proper comprises a yoke shaped member composed of a body 8 and arms 9, which are slidably mounted in openings in the body 4 of the back frame and the cross bars 6 and 7. When the yoke 8 and 9 is contracted, the body 8 thereof lies adjacent to the body 4 of the back frame, and the arms 9 of the yoke are engaged with all of the openings of the elements 4, 6 and 7.

The yoke may be extended by drawing it out as shown in Fig. 1, and may be held firmly in extended position, by withdrawing the free ends of the arms 9, from the openings in the cross bar 6, and engaging the free ends with struck up loops or wickets 10 in the cross bar.

Referring to Figs. 1 and 2, it will be seen that the cross bars 6 and 7 which are also of angle material, are arranged with one portion substantially horizontal, and the other portion substantially vertical when the stand is unfolded. The openings for the yoke arms 9 are in the horizontal portions of the arms, while the loops or wickets 10 are in the vertical portion of the cross bar 6.

These loops or wickets 10 as shown in Fig. 3 are spaced somewhat rearwardly of the openings for the yoke arms, so that when the free ends of the yoke arms are engaged with the loops, they will rest upon the horizontal portion of the cross bar, and the arms are of such length that in retracted position

they will pass through the openings in the cross bar 7.

A plurality of cards 11, each of which carries display matter relating to the goods supported by the stand, is supported by the body 8 of the yoke. Each card has a pair of reinforced openings 12 at its upper side edge, and these openings are engaged by rings 13 on the yoke body. As shown the 10 openings are eyeletted, and the arrangement is such that they may be swung to the front of the stand back frame into display position, or rearwardly thereof as indicated in Fig. 3. It will be obvious that both faces of each card may be provided with display matter, so that such matter is visible from in front and in rear of the stand.

In order to prevent the rings 13 from dropping over onto the arms of the yoke, 20 integral extensions 14 are provided at the junction of the body and arms. These extensions are long enough to prevent the rings dropping over the angle between body and arms. In the present instance the yoke is 25 formed from a wire rod of suitable size, and the extensions are formed by doubling the rod upon itself.

When the stand is filled with goods, the back extension may be moved to the posi-

tion of Fig. 2, and as the merchandise is disposed of and the pile decreases in height, the extension may be moved into the position of Fig. 2. In either case, the cards may be swung from the back to the front of the frame, to display any card.

I claim:

1. A display stand, including a back frame having cross bars provided with vertical aligned sets of openings, and an extension having rods slidable in the openings, one of the bars having sockets adjacent the openings for engagement by the ends of the rods when free from the openings to support the extension, in extended position.

2. In a display stand a back frame having sets of vertically aligned bearings and sockets laterally offset from the bearings of an intermediate set, an extension frame having rods slidable in the bearings and resilient to be displaced laterally into the sockets when said rods are withdrawn from the bearings adjacent thereto, thereby to support the extension extended.

Signed at Dayton in the county of Montgomery and State of Ohio this 27th day of July A. D. 1925.

EDWARD B. WESTON.
